Primary Examiner — Rhea Shields*(74) Attorney, Agent, or Firm* — Tarolli, Sundheim, Covell & Tummino LLP; John A. Yirga, Esq.(57) **CLAIM**

The ornamental design for a part of hair brush, as shown and described.

DESCRIPTION

FIG. 1 is a front elevation view of a part of hair brush in accordance with our ornamental design;

FIG. 2 is a rear elevation view thereof;

FIG. 3 is a bottom plan view thereof;

FIG. 4 is a top plan view thereof;

FIG. 5 is a rear perspective view thereof;

FIG. 6 is a right side elevation view thereof;

FIG. 7 is a front perspective view thereof; and,

FIG. 8 is a left side elevation view thereof.
